CLAIM

We claim the ornamental design for an integrated volume and back button on a remote control unit, as shown and described.

DESCRIPTION

FIG. 1 is a top view of a remote control unit including the integrated volume and back button;

FIG. 2 is a bottom view thereof;

FIG. 3 is a left side view thereof;

FIG. 4 is a right side view thereof;

FIG. 5 is a rear view thereof;

FIG. 6 is front view thereof; and,

FIG. 7 is top view of an integrated volume and back button on a remote control unit showing a second embodiment of our new design.

The broken line showings of the remote control unit are for the purposes of illustrating environmental structure and form no part of the claimed design.

1 Claim, 4 Drawing Sheets
